US0D1078417S

(12) **United States Design Patent** (10) Patent No.: **US D1,078,417 S**
(45) Date of Patent: ** Jun. 10, 2025

(54) **TRIANGLE CURB BOX WRENCH**

(71) Applicant: **Jianxia Gao**, Anqiu (CN)

(72) Inventor: **Jianxia Gao**, Anqiu (CN)

(**) Term: **15 Years**

(21) Appl. No.: **29/983,267**

(22) Filed: **Jan. 9, 2025**

(51) LOC (15) Cl. **08-05**

(52) U.S. Cl.

USPC **D8/21**

(58) **Field of Classification Search**

USPC D8/24, 107, 21, 22, 25; D10/83

CPC B25B 23/1425

See application file for complete search history.

(57) **CLAIM**

The ornamental design for a triangle curb box wrench, as shown and described.

DESCRIPTION

FIG. 1 is a top perspective view of a triangle curb box wrench, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the triangle curb box wrench, which form no part of the claimed design.

1 Claim, 8 Drawing Sheets
